UNITED STATES PATENT OFFICE

2,169,439

SURFACE DECORATING METHOD AND APPARATUS

Guido von Webern, Dayton, Ohio, assignor to Oxford Varnish Corporation, Detroit, Mich., a corporation of Michigan

Original application April 23, 1935, Serial No. 17,825. Divided and this application November 11, 1936, Serial No. 110,361

5 Claims. (Cl. 101—37)

This application is a division of my copending application for Letters Patent, Serial No. 17,825, filed April 23, 1935. The present invention relates to an improved method and apparatus for feeding and delivering work to and from a decorating machine, and especially to such as a rotary printing or graining machine adapted and arranged to decorate the articles in simulation of natural objects. This, therefore, is the general object of the invention.

A more specific object of the invention is to provide an improved decorating method and apparatus for delivering comparatively small articles, such as small pieces of leather or other flexible similar materials, to a surface decorating or graining machine.

Another object is to provide a work delivering mechanism for a surface decorating machine, which mechanism will smooth out the article to be decorated, so that articles, such as small pieces of leather and the like, may be decorated without danger of folding or creasing the articles.

A further object of the present invention is the provision of an improved apparatus which will expedite the feeding of work to and from a surface decorating machine, such as a rotary printing or graining machine, and which apparatus will facilitate the decoration of leather, cloth and other similar articles with rapidity and ease, even though such articles be comparatively small.

Other objects of the present invention will become more apparent from the following description, reference being had to the preferred form of mechanism for carrying out the method. The essential features of the invention will be set forth in the claims.

In the drawings, Fig. 1 is a side elevation of a preferred form of my improved work handling mechanism, as used with a decorating machine of the type shown, described and claimed in my copending application, heretofore referred to; Fig. 2 is a side elevation of the opposite side of the machine from that shown in Fig. 1; Fig. 3 is a horizontal section taken along the line 3—3 on Figs. 1 and 2; Fig. 4 is a vertical section, as indicated by the line 4—4 on Figs. 1 and 2; Fig. 5 is a sectional detail, the plane of the section being indicated by the line 5—5 on Fig. 1; Fig. 6 is a diagram illustrating a step in the method used when decorating relatively small flexible articles, such as leather, or the like.

The decorating mechanism, as shown in the drawings, will first be described. Referring to

Figs. 1 and 2, it will be seen that there is provided a pair of side frame members 10 and 12, which are connected together by cross-frame members 11. Supported on these side frame members are suitable bracket arrangements for respectively supporting a pattern roll 15, a transfer or offset roll 16, an inking roll 17, together with a platen roll 18.

The pattern roll may be an intaglio cylinder comprising a continuous etched copper plate, and is arranged to contact with the surface of an offset or transfer roll 16. The offset roll 16 is mounted on a shaft 20, the ends of which are journaled in rock arms 21. These arms are pivotally mounted on a shaft 22, supported by the frame members 10 and 12, and are retained in their normal or active positions by a pin 25 carried by one of the arms 21 (Figs. 1 and 5), which is engaged by a cam slot 26 in a pivoted lever 27. When the pin 25 is in the left-hand portion of the slot 26, as shown in Fig. 1, the offset roll 16 is maintained in its active position, whereas, when the pin is in the right-hand portion of the slot 26, the offset roll 16 is out of contact with the pattern roll. A spring-pressed plunger 28, carried by the lever 27, cooperates with openings 29 in the frame member 10, to selectively maintain the lever in the desired position.

The platen roll 18 is mounted on a shaft 30, supported in brackets 31, pivoted as at 32, to the frame members 10 and 11. Pressure screws 33, carried by the respective frame members 10 and 11, urge the platen roll upwardly into contact with the offset roll and thereby provide a printing pressure.

The ink roll 17 is drivingly carried by a shaft 35, the ends of which are journaled in respective levers 37, which are pivotally mounted as at 36, adjacent the frame members 10 and 11. The ink roll supporting levers are secured in adjusted positions, with its lower portion submerged in fluid color carried in a reservoir or pan 75, by suitable clamping bolts 40 carried by respective frame members. The pattern roll 15 is drivingly secured to a suitable shaft 41, which is journaled in upstanding brackets or arms 42 of the frame members 10 and 12.

The various rolls are driven by a motor 50. As shown in Figs. 2 and 3, the motor 43 is drivingly connected to a speed reduction unit 44. The driven shaft of the reduction unit is provided with a bevelled pinion 45, which meshes with a bevelled pinion 46, drivingly secured to a shaft 47. The shaft 47 is mounted in bearings 55.

48, carried by a frame member 11, and is provided with a bevelled pinion 49, arranged to mesh with a bevelled gear 50, carried by a shaft 51, journalled in the frame member 11.

5 The shaft 51 drives the offset and inking rolls 16 and 17. Mounted on this shaft and drivingly connected to the bevelled gear 51, is a gear 52 arranged to mesh with a pinion 58 drivingly mounted on a shaft 54 which is journalled in the 10 frame member 11. Drivingly connected to the pinion 58 is a pulley 59, which, through the medium of a belt 60, and pulleys 61 and 62, drives the ink roll shaft 35 and the offset roll shaft 20, respectively.

15 Drivingly secured to the shaft 47 is a bevelled pinion 63. This pinion meshes with a bevelled gear 64, which is drivingly secured to the pattern roll shaft 41.

20 As heretofore mentioned, the decorating machine is especially arranged for use on an intaglio printing roll. I therefore provide a scraper or doctor blade mechanism which acts to remove excess color or ink from the roll, leaving color only in the low portions or pockets of the pattern.

25 The doctor blade comprises a thin metallic blade 65, which is rigidly supported on a shaft 66, carried by frame brackets 67. A weight 68 (Fig. 1) carried by an arm 69 is rigidly secured to the doctor blade shaft 66, and maintains the blade 30 in contact with the periphery of the pattern roll.

Any ink which may remain on the offset roll 16, after the pattern has been transferred to the work, is removed by a scraper 70. As illustrated in Fig. 2, the scraper 70 is mounted on a shaft 71, the ends of which are carried by arms 72 pivoted as at 73 to the frame and provided with suitable adjusting screws 74, arranged to engage the frame to vary the pressure of the blade on the roll.

40 The decorating mechanism just described is, in general, typical of machines which are at present used for the surface decoration of many articles. It is obvious that articles made of metal, paper or other materials, having sufficient 45 rigidity to permit them to be shoved into the bite of the offset and platen rolls, may be readily decorated by such types of machines. However, flaccid articles made of leather or other flaccid materials are difficult to decorate, in that they have insufficient rigidity to permit them to be fed into the bite of the offset and platen rolls in the same manner as metal, or even paper articles are fed. The present invention is especially concerned with the provision of a 50 comparatively simple method of decorating such articles, together with an improved mechanism to feed the articles to a decorating machine, as, for instance, a rotary graining machine of the type just described.

55 My improved method comprises continuously feeding a substantial web or belt 80 of paper or fabric between the offset and platen rolls, and temporarily securing the articles to be decorated to this web before it enters the bite of these rolls, and without interrupting the progress of the web. The articles are secured to the web either by adhesive carried by the web or by gummed wafers. After the articles have passed between the offset and platen rolls, they are 60 removed from the web, without interrupting the progress thereof.

65 The web 80 may be in the form of a continuous loop, or, as shown in Figs. 1 and 2, it may be a substantially continuous web, in roll form. 70 As illustrated, the web is drawn upwardly from

a roll of material 81, carried by brackets 82, and passes around a guide roll 83, supported by a table 86. The web passes across the table (toward the left in Fig. 1) into the bite of the offset and platen rolls, as will be hereinafter more 5 fully described. As the web passes across the table, the operator secures thereto the work, such as the leather article indicated at W, in Figs. 2 and 3. These articles are secured to the web either by a tacky gum or suitable adhesive carried by the web. However, I have shown the article as being secured to the web by adhesive coated stickers or wafers 85. A continuous canvas or fabric belt 86, looped about drums 87 and 88, presses the work into intimate contact with 10 the web and a spring-pressed roller 89 urges the belt, the articles and the web into intimate contact with the table top, thereby smoothing the articles and securely affixing the articles to the 15 web.

20 Adjacent the forward or left-hand end of the belt 86, I provide a pair of ironing bars 90 and 91. The bar 90 as shown in Fig. 1, has eccentric end portions 92 journalled in respective frame members 10 and 11. This bar is arranged to be 25 clamped in an adjusted position relative to the frame by a clamp 93, preferably threadingly engaging one end of the rod and clamping it to the frame plate 10. The other ironing bar or rod 91 engages the paper web 80 between the 30 bar 90 and the forward drum 88, about which the belt 86 is looped. The bar 91 is carried by a pair of arms 94, pivotally mounted on a shaft 95 which is carried by the frame members 10 and 11. The levers 94 are rocked about their 35 pivots by respective cams 96 carried by stub shafts 97 which are journalled in respective frame members 10 and 11. These stub shafts are arranged to be swung by suitable adjusting screws 98. Each adjusting screw is carried by 40 a frame boss 99 and acts against a lever 100, which is secured to its respective stub shaft 97. In this way the pressure on the web may be 45 adjusted to smooth or iron out any wrinkles in the hides or articles.

50 The fabric belt 86 is preferably driven at the same rate of peripheral speed as the peripheral speed of the platen roll 18. As shown in Figs. 2 and 3, the rearmost drum or roller 87, about which the belt 86 is looped, is provided with a 55 pulley 105. This pulley, through the medium of a belt 106, is driven by a pulley 107, drivingly mounted on the shaft 54 heretofore described in detail.

55 The workpieces W are stripped from the paper web 150 after the impressions have been made thereon by a stripper or knife 110. As shown in Fig. 2, the knife 110 comprises a thin metallic blade, carried by a table 112, from which the workpieces may be removed by the operator, 60 or may drop onto a conveyor 114 of any well-known type.

65 The web 80 is rewound on a take-up reel 115, which may be driven by a pulley 116, frictionally connected to the take-up roll in the usual manner. This pulley is driven by a driving belt 117 from a pulley 118, carried by a shaft 112, which is journalled in the frame member 10 and is provided with a spur gear 119, which meshes with the gear 52, heretofore described.

70 From the foregoing description, it is obvious that I have provided an improved method and apparatus for facilitating the decoration of flexible articles, especially small leather or similar articles. My improved apparatus irons or 75

smoothes out any wrinkles in the articles, prior to their decoration and is so arranged as to permit operation of the decorating mechanism without any interruption for feeding articles thereto.

5 I claim:

1. A surface decorating machine including an impression roll, a substantially continuous flexible web, means to progress the web to bring flexible articles placed thereon into contact with the transfer roll, and means to smooth out the articles before they reach the impression roll, said last-named means including a flexible belt having one stretch thereof in intimate contact with the first-named web and the articles thereon.

10 2. In a surface decorating machine a substantially continuous web adapted to receive workpieces, a flexible belt having one stretch thereof in engagement with the web, means to progress the web and the belt, and means to tension the web and belt to thereby smooth out workpieces gripped therebetween, and means acting thereafter to transfer a pattern to the articles on the web.

15 3. In a surface decorating machine, a pattern roll, a substantially continuous web adapted to receive workpieces, a looped belt, means to cause one stretch thereof to contact with said web whereby workpieces may be gripped between the belt and the web, supporting means for said web 20 at the point of engagement with said belt, and means acting in opposite directions and engaging the web and belt respectively to smooth out the articles gripped thereby, means acting thereafter to transfer the pattern to the articles on the

25 web, and means to progress said belt and web and rotate said rolls.

4. In a surface decorating machine, an impression roll, a substantially continuous web adapted to receive workpieces, means to progress said web, a looped belt having one stretch thereof adapted to engage the workpieces on the web, means to progress said belt, a pair of ironing bars, one of said bars engaging the looped belt and the other engaging the web, means to move one of said bars to tension the web and belt gripped thereby and smooth out the articles gripped between the web and the belt, means to rotate said roll to transfer the pattern to the smooth articles on the web, and means acting thereafter to remove the decorated articles from the web.

5. In a surface decorating machine, an impression roll and a coacting platen roll, a substantially continuous web passing between said rolls and adapted to receive workpieces, a pair of spaced rolls mounted above said web and having a continuous belt looped thereabout, one stretch of said belt being substantially parallel with and in contact with said web, whereby workpieces may be gripped between the belt and the web, 25 an ironing bar, said bar being disposed between said spaced rolls and engaging the belt, means movable into contact with said web intermediate the bar and one of said last-named rolls to tension the web and belt as a unit, means to progress 30 the web and belt and rotate said roll to transfer a pattern to the articles on the web, and means acting thereafter to remove the decorated articles from the web.

GUIDO von WEBERN. 35
